DESIGN FOR A COMBINED MAGNIFYING GLASS AND PAPER WEIGHT

Bernard Lubow, New York, N. Y.

Application June 19, 1944, Serial No. 114,092

Term of patent 14 years

(Cl. D57—1)

To all whom it may concern:

Be it known that I, Bernard Lubow, a citizen of the United States, residing at New York, in the county of New York and State of New York, have invented a new, original, and ornamental Design for a Combined Magnifying Glass and Paper Weight, of which the following is a specification, reference being had to the accompanying drawing, forming a part thereof.

In the drawing:

Fig. 1 is a perspective view of a combined magnifying glass and paper weight, showing my new design.

Fig. 2 is a bottom plan view, and

Fig. 3 is a side elevational view of the same.

I claim:

The ornamental design for a combined magnifying glass and paper weight, as shown.

BERNARD LUBOW.
